United States Patent Office

Des. 180,016
Patented Apr. 9, 1957

180,016

DOLLY

William H. Frick, Cleveland, Ohio

Application May 2, 1956, Serial No. 41,314

Term of patent 14 years

(Cl. D14—3)

FIG. 1

FIG. 3

Fig. 1 is a perspective view of a dolly, embodying my new design;

Fig. 2 is a side elevational view; and

Fig. 3 is a front elevational view.

I claim:

The ornamental design for a dolly, as shown.
